UNITED STATES PATENT OFFICE

2,515,707

ATTACHMENT HOLDER FOR SEWING MACHINES

Arthur N. Hale, Stratford, Conn., assignor to The Singer Manufacturing Company, Elizabeth, N. J., a corporation of New Jersey

Application June 7, 1946, Serial No. 675,079

3 Claims. (Cl. 112—257)

1

This invention relates to improvements in means for securing sewing machine attachments in their proper operative position and it relates more particularly to securing means for that type of attachment disclosed, for example, in the U. S. Patents of C. Reynolds, No. 613,604, November 1, 1898, and E. J. Swanson, No. 2,173,509, September 19, 1939, which is capable of application to and removal from the bed-plates of sewing machines.

The attachment disclosed in the above mentioned patents is the well known scroll-type hemmer and is adapted to be fastened in position on the bed-plate of a sewing machine by means of a threaded stud which depends from one end of the base-plate of the attachment and extends through a locating hole in the sewing machine bed-plate, the stud having threaded thereon a wing-nut which clamps the attachment in position. To assist in properly aligning the delivery end of the attachment with the stitching instrumentalities of the sewing machine, the other end of the base-plate of the attachment is downturned to form a lip adapted to enter a locating hole provided in the usual throat-plate of the sewing machine. The depending stud with its wing-nut and the downturned lip effectively hold the attachment in its proper position and can be employed successfully on attachments adapted to be mounted on sewing machines having no mechanism beneath the front portion of the bed in the space to be occupied by the wing-nut.

However, in the more modern high speed sewing machines having mechanism arranged beneath the front portion of the bed-plate, such for example as sewing machines of the types disclosed in the United States Patents Nos. 2,151,308 and 2,332,125, the screw-stud and wing-nut attachment-holding means is not practical. Since the attachment disclosed in the Swanson patent is well known and used extensively in the commercial manufacture of handkerchiefs and neckties, it is desirable that means be provided whereby attachments of this type can be applied quickly and conveniently to the bed-plates of the high speed sewing machines now offered to the trade.

Therefore, it is the primary object of the present invention to provide attachment-holding means of simple design which is operable to secure attachments of conventional construction in proper operative position on the bed-plate of a sewing-machine, said attachment holding means requiring only a simple change in the construction of the usual "bed slide-plate," which is used to cover the opening through which access may be had to the loop-taker.

Another object of the present invention is to provide an attachment-holder by which an attachment of the conventional scroll-hemmer type

2

may be secured in working position by simply withdrawing the bed slide-plate, placing the scroll-hemmer in the proper location, and then closing the bed slide-plate.

With these and other objects in view my invention consists in the construction, arrangement and combination of the various parts of my improvement, whereby the objects contemplated are attained, as hereinafter more fully set forth, pointed out in my claims, and illustrated in the accompanying drawings, in which:

Fig. 1 is a perspective view, partly in section, of a sewing machine embodying the present invention, showing the manner in which the improvement operates to secure a conventional scroll-hemmer in operative position on the machine bed-plate.

Fig. 2 is a top plan view of a portion of the sewing machine bed-plate with the bed slide-plate closed, illustrating the manner in which the attachment base-plate, shown in dot-and-dash lines, is clamped in proper position.

Fig. 3 is a vertical sectional view taken substantially along the line 3—3, Fig. 2.

Fig. 4 is a bottom plan view of the bed slide-plate fitted with my improved attachment clamping means.

Referring to the drawings, the sewing machine illustrated comprises a machine-frame including a flat-top bed-plate or work-support 10 overhung by a bracket-arm terminating in a head 11 in which is journaled for endwise reciprocation a needle-bar 12 carrying at its lower end a needle 13. Formed in the bed-plate 10 is an opening 14 having parallel side edges 15 merging into a rounded inner end 16. The inner end portion of the opening 14 is adapted to be closed by a throat-plate 17 secured in place by screws 18, the throat-plate being formed with a needle-aperture 19 and feed-dog slots 20. Operating through the slots 20 is a conventional feed-dog 21 against the serrated surface of which the work is held by a presser-foot 22 carried on the lower end of the usual spring-depressed presser-bar 23. Along the parallel side edges 15 of the opening 14, the bed-plate 10 is provided with an upwardly open recessed guideway 24 affording a seat for a plate-member or bed slide-plate 25. The bed slide-plate 25 is confined to sliding movements in the guideway 24 and when normally closed its inner end 26 abuts against the throat-plate 17 and its outer end 27 is substantially flush with the end of the bed-plate 10. The bed slide-plate 25 is held seated in the guideway 24 by a member 28 suitably secured to the under side of the slide-plate and from the opposite ends of which extend wings 29 comprising underhung spring means adapted slidably to engage the under side of the bed-plate 10 at opposite sides of the

opening 14 and yieldingly to confine the slide-plate 25 to sliding movements in the guideway 24.

To adapt the sewing machine to receive an attachment of the type shown in Fig. 1, which comprises complementary scroll members 30 and 31 carried on a shank 32 suitably fastened on a flat base-plate 33 having at one end a depending securing stud 34 and at its other end a down-turned positioning-lip 35, the bed-plate 10 is apertured as at 36 and the throat-plate 17 is apertured as at 37. The two apertures 36 and 37 provide locating holes for the attachment and preferably are sized slightly larger than the stud 34 and the downturned positioning-lip 35 of the attachment, thus permitting the latter to be conveniently applied to the machine in proper aligned position with the stitching mechanism.

To provide for maintaining the attachment in operative position with its securing stud and positioning-lip in their respective locating holes, the bed slide-plate 25 is equipped with means for clamping the attachment seated on the bed-plate 10. To that end, the slide-plate 25 adjacent its inner front corner is recessed, as at 38, in its under face to receive a plate-element 39 fastened, preferably by rivets 40, to the slide-plate. The plate element 39 is formed with an upwardly bent laterally extending spring-finger 41 disposed so that its under surface is located above the level of the upper surface of the slide-plate, thereby to slide over the base-plate 33 of the attachment. The spring-finger 41 is relatively stiff and is shaped to maintain the base-plate of the attachment firmly seated on the bed-plate 10 of the sewing machine. The leading or free end of the spring-finger 41 is bent upwardly slightly so that when the slide-plate 25 is closed to effect a clamping of the attachment in its operative position the finger 41 will readily ride over the edge of and on the base-plate 33 of the attachment.

To assist in holding the attachment on the bed-plate 10 and to prevent the bed slide-plate 25 from yielding vertically out of its guideway 24 when the spring-finger 41 slides on the attachment base-plate 33, the plate-element 39 is formed with a second laterally projecting spring-finger 42 vertically spaced below the spring-finger 41 to engage the under side of the throat-plate 17, as shown in Fig. 3. The free end of the spring-finger 42 is bent downwardly slightly to facilitate the sliding of the finger beneath the throat-plate 17.

From the above description, it will be evident that in applying the attachment to the machine it is only necessary partially to retract the bed slide-plate 25, place the attachment flat on the bed-plate 10 in proper position with its securing stud 34 and positioning-lip 35 in their respective holes 36 and 37, and then return the bed slide-plate to its normally closed position. The opposed spring-fingers 41 and 42 effectively clamp the attachment in its proper aligned position determined by the holes in the bed-plate 10. It will be understood that no change whatever in the conventional attachment is necessary in order to mount it on a sewing machine equipped with the present invention. The extent of modification of the machine required in applying the present attachment-holding means thereto is small and of the simplest kind. It will be appreciated that the attachment-clamping spring-fingers 41 and 42 need not be substantially sprung or distorted when they are moved into attachment-clamping position and, consequently, long

life of the spring-fingers is assured. Moreover, the upper spring-finger 41 is shaped so that it substantially rests directly on the throat-plate when the attachment is removed from the sewing machine. This is desirable in that the spring-finger 41 does not interfere with the passage of work across the bed-plate when flat work is being stitched.

While I have referred to the fingers 41 and 42 as being spring fingers, it will be understood that these fingers may be made of substantially heavy stock so that they are rigid. In that case the spacing between the under face of the finger 41 and the upper face of the finger 42 must be accurately maintained and of a size equal to the combined thickness of the throat-plate 17 and attachment base-plate 33 (Fig. 3).

Having thus set forth the nature of the invention, what I claim herein is:

1. An attachment-holder for a sewing machine having a bed-plate provided with a clearance-opening defined by parallel guideways, comprising, a bed slide-plate adapted to slide in said guideways, and a plate-element secured to said bed slide-plate, said plate-element terminating in vertically spaced opposed attachment-clamping fingers projecting beyond one end of said slide-plate, one of said fingers having its under surface disposed above the level of the upper surface of said slide-plate and the other of said fingers disposed below the under surface of said slide-plate so that the act of sliding the slide-plate into its clearance-opening closing position will cause one of said fingers to ride on and engage the attachment and the other of said fingers to ride under and engage said bed-plate.

2. An attachment-holder for a sewing machine having a bed-plate provided with a clearance-opening defined by parallel guideways, comprising, a bed slide-plate adapted to slide in said guideways, and a plate-element secured to the under side of said bed slide-plate, said plate-element being formed with two vertically spaced opposed attachment-clamping fingers projecting beyond the inner end of said slide-plate, one of said fingers being bent upwardly and then horizontally so that its under surface is disposed above the level of the upper surface of said slide-plate, and the other of said fingers is shaped so that it is disposed below the under surface of said slide-plate.

3. An attachment-holder for a sewing machine having a bed-plate provided with a guideway, comprising, a plate-member adapted to slide in said guideway, said plate-member having an attachment-clamping spring-finger rigidly fastened to said plate-member and projecting laterally therefrom beyond one of its edges, said spring-finger having its under surface located above the level of the upper surface of said plate-member in attachment-clamping relation with said bed-plate.

ARTHUR N. HALE.
